UNITED STATES PATENT OFFICE.

BENJAMIN F. FOWLER, OF MINNEAPOLIS, MINNESOTA, ASSIGNOR, BY MESNE ASSIGNMENTS, TO THE BING BURNER COMPANY, OF MINNEAPOLIS, MINNESOTA, A CORPORATION OF MINNESOTA.

LAMP-BURNER.

SPECIFICATION forming part of Reissued Letters Patent No. 12,342, dated May 2, 1905.

Original No. 735,236, dated August 4, 1903. Application for reissue filed January 18, 1905. Serial No. 241,701.

To all whom it may concern:

Be it known that I, BENJAMIN F. FOWLER, a citizen of the United States, residing at Minneapolis, in the county of Hennepin and State 5 of Minnesota, have invented a new and useful Lamp-Burner, of which the following is a specification.

This invention relates to lamp-burners; and one of the objects thereof is to provide a novel 10 construction of a transparent cone which will permit the escape of all the rays of light from the flame and will diffuse them evenly, especially when the light is turned low.

Another object is to provide a novel device 15 by means of which the flame may be easily trimmed, said device also serving to protect the cone against the flame, and thus avoiding its being broken.

The preferred form of construction is fully 20 illustrated in the accompanying drawings, though it will be understood that various changes may be made from this construction.

In said drawings, Figure 1 is a perspective view of a lamp-burner constructed in accordance 25 with the present invention. Fig. 2 is a vertical sectional view through the same. Fig. 3 is a similar view taken at right angles to Fig. 2. Fig. 4 is a horizontal sectional view. Fig. 5 is a detail vertical sectional view through 30 a slightly-modified form of construction. Fig. 6 is a horizontal sectional view through the same.

Similar numerals of reference designate corresponding parts in all the figures of the 35 drawings.

In the embodiment of the invention, as shown, the body is constructed of substantially the usual shape, having a threaded boss 10, outstanding flange 11, the perforated 40 platform 12, and the upright wick-tube 13. To this body is connected a metallic collar 14, which, as shown, is hinged at 15, its opposite side being provided with a suitable latch 16, though other means of connection may be 45 employed, if desired. The upper edge of this collar is preferably flush with the upper

end of the wick-tube, and said collar supports the cone 17. The cone is of some transparent material, preferably of glass, shown as being formed of one piece, though, 50 as will be readily understood, it may be of more, if desired. Its upper portion is of the usual form, being provided with a flame-opening 18, located directly above the wick-tube. Upon the lower portion of the cone to a slight 55 distance above its lower edge is arranged an annular horizontal rib 19, this rib being provided with outstanding substantially pyramidal projections 20. The lower end of the cone fits within the collar 14, the rib 19 constituting a stop against which the upper edge 60 of said collar abuts.

Mounted upon the wick-tube is arranged a device which may be termed a "flame-trimmer," this device being in the form of a horizontally-disposed spreader plate or platform 21, having a central opening 22, through which the wick-tube passes, this opening being longer than the width of the tube, so that the trimmer may be moved longitudinally. 65 The plate is provided on opposite sides of the opening with upstanding flanges 23, which bear against the opposite sides of the wick-tube and form extended bearing-surfaces to properly support the trimmer. 70

The burner is employed in the customary manner; but it will be seen that when the light is turned low the rays therefrom will readily pass through the cone, and especially 75 through that portion thereof which carries the rib. As a result the light passing through the rib will be diffused by the projections. The burner is therefore especially useful on night-lamps, as it may be turned down so that no direct rays of light will emanate from the 80 lamp, though the room will be sufficiently illuminated. When the light is turned up, the direct rays can of course pass through the clear and unbroken upper portion of the cone, so that no light is lost. Should the wick be 85 trimmed unevenly and the flame flare at either corner, by moving the trimming-plate longi- 90

tudinally in one direction or the other, or, in other words, transversely of the wick-tube the draft to the higher portion of the flame may be cut off, and thus the flame may be 5 trimmed. In this way the danger of breaking the cone by the flame striking it is avoided. This trimming operation can be readily accomplished, for by throwing back the cap access is obtained to the spreader-plate.

10 In Figs. 5 and 6 a slightly-modified form of construction is shown. The construction as above described is still employed; but the metallic collar 14 is provided with a plurality of 15 perforations, which may be in the form of circular openings 24, as shown, or they can be of any shape desired. A transparent shield 25 is located within the collar and covers the opening, said shield being preferably formed of mica. This arrangement permits the greater 20 radiation of light and at the same time the shield prevents the ingress of lateral drafts of air.

From the foregoing it is thought that the 25 construction, operation, and many advantages 25 of the herein-described invention will be apparent to those skilled in the art without further description, and it will be understood that various changes in the size, shape, proportion, and minor details of construction may 30 be resorted to without departing from the spirit or sacrificing any of the advantages of the invention.

Having thus described my invention, what I claim as new, and desire to secure by Letters 35 Patent, is—

1. In a lamp-burner of the class described, a cone constructed of transparent material and having on its outer face an annular series 40 of outstanding and substantially pyramidal-shaped projections arranged contiguous to its lower end, the portion of the wall above the series being smooth to permit the direct passage of rays of light.

2. In a lamp-burner of the class described, 45 a cone constructed of transparent material and having an annular rib arranged above its lower edge, a metallic collar fitted upon the lower end of the cone, and an annular series of outwardly-projecting angular and tapering 50 transparent projections, arranged upon the rib and projecting over the collar.

3. In a lamp-burner, a wick-tube, a transparent cone covering the tube and having a flame-opening located above the same, said 55 cone having an annular rib on its outer face above its lower edge, a metallic collar fitted upon the lower end of the cone and resting against the rib, the upper end of the collar being substantially flush with the upper end 60 of the wick-tube.

4. In a burner, a wick-tube, a cone extending over the same, and a spreader-platform mounted upon the tube and surrounding the

same, said spreader-platform being located inside the cone and movable transversely of the 65 tube independently of said cone.

5. In a burner, a wick-tube, a cone extending over the same, and a substantially horizontal spreader-platform surrounding the tube and movable transversely thereof independently of the cone, said platform being located inside the cone and having upright flanges engaging opposite sides of the tube.

6. In a burner, a body having an upstanding wick-tube, a metallic collar secured to the 75 body about the wick-tube, a glass cone fitted within the upper edge of the collar and having a rib on its outer face, said rib being provided with an annular series of pyramidal-shaped projections, a horizontally-disposed 80 spreader-plate frictionally supported upon the upper end of the wick-tube, said plate being longitudinally adjustable upon the tube.

7. In a burner, a body having an upstanding wick-tube, a metallic collar secured to the 85 body about the wick-tube, a glass cone fitted within the upper edge of the collar and extending above the wick-tube, said cone having an outstanding rib provided with an annular series of outstanding pyramidal projec- 90 tions.

8. In a burner, a body having an upstanding wick-tube, a horizontally-disposed 95 spreader-plate frictionally supported upon the upper end of the wick-tube, said plate being 95 adjustable transversely of the tube, and a cone extending over the tube and plate and housing the same, said plate being movable with respect to the cone.

9. In a lamp-burner, a body having a per- 100 forated platform, a threaded boss, and a wick-tube extending from the platform, in combination with a metallic collar displaceably mounted on the platform and surrounding the wick-tube, and a cone constructed wholly of 105 glass extending over the wick-tube and having its lower end fitted within the collar, said cone having a flame opening and constituting the sole burner dome or cover for the tube, said collar terminating on a line with or below the upper end of the tube to permit the unobstructed lateral passage of light from the flame through the glass cone both outwardly and upwardly when said flame is turned low.

10. In a lamp-burner, a body having a per- 115 forated platform, a threaded boss projecting from one side of the platform, and a wick-tube extending through the boss and platform and projecting above the side of said platform opposite the boss, in combination with an im- 120 perforate metallic collar terminating on a line with or below the upper end of the wick-tube hinged to the platform with its lower edge normally fitting thereon and surrounding the projecting portion of the wick-tube, and a 125 cone constructed wholly of glass extending

over the wick-tube and having its lower end snugly fitted within the collar, said cone having a flame-opening in its top and constituting the sole burner dome or cover for the tube, whereby the unobstructed lateral passage of light from the flame is permitted outwardly and upwardly through the glass cone when said flame is turned low.

In testimony that I claim the foregoing as my own I have hereto affixed my signature in the presence of two witnesses.

BENJAMIN F. FOWLER.
